SHUFFLEBOARD GAME DEVICE

Raymond J. Lohr and Laurie May Campbell, Erie, Pa.,
assignors to Louis Marx & Co., Inc., New York, N.Y.

Filed May 12, 1972, Ser. No. 252,963

Term of patent 14 years

Int. Cl. D21—01

U.S. Cl. D34—5 BB

FIG. 1 is a front perspective view of a shuffleboard game device with the elevated track shown in the closed folded-in position;

FIG. 2 is a view similar to FIG. 1 with the track shown in elevated open position;

FIG. 3 is a front elevational view thereof;

FIG. 4 is a top plan view thereof;

FIG. 5 is a side elevational view thereof; and

FIG. 6 is a rear elevational view thereof.

We claim:

The ornamental design for a shuffleboard game device, as shown.
